(57) **CLAIM**

The ornamental design for a in-ceiling 3-way minimal opening bandpass speaker as shown and described.

DESCRIPTION

FIG. 1 is a bottom perspective view of an in-ceiling 3-way minimal opening bandpass speaker showing my new design;

FIG. 2 is a top perspective view thereof;

FIG. 3 is a front view thereof;

FIG. 4 is a back view thereof;

FIG. 5 is a left view thereof;

FIG. 6 is a right view thereof;

FIG. 7 is a bottom view thereof;

FIG. 8 is a top view thereof; and,

FIG. 9 is a cross sectional view showing the interior thereof. Any broken line illustration is of environmental structure in the drawing, and is not part of the design sought to be patented.
